MUSKETRY TRAINING DEVICE

Zygmunt de Lubicz-Bakanowski, Frederick John Minns, and Garnet Wilfred Glover Norman, Oxford, England, assignors to The Swift Rifle Company Limited, Oxford, England

Application January 11, 1943, Serial No. 472,072
In Great Britain August 19, 1941

6 Claims. (Cl. 35—25)

This invention relates to musketry and like training devices comprising a dummy gun adapted, when the trigger is pulled, and after cocking, to project a rod having means for piercing a target.

The object of the invention is to provide a simple cocking and trigger mechanism employing a small number of parts for devices of the kind referred to.

In a musketry and like training device of the kind referred to made according to the present invention the cocking and trigger mechanism comprises a hollow bolt, a striker mounted within the bolt, a main spring mounted on the striker between an abutment fixed to the bolt and an abutment carried on the striker, a cocking piece arranged to engage the striker, a sear arranged to engage the cocking piece and to hold it and the striker immovable against the pressure of the main spring when the gun is cocked by backward and forward movement of the bolt, and a trigger arranged to actuate the sear to release the cocking piece and, consequently, the energy of the cocked spring to actuate the striker whereby the piercing end of the latter is projected from the gun.

The bolt has a bayonet slot engaged by an abutment on the cocking piece, permitting the bolt to be slidden backwards and forwards, and rotated, relatively to the cocking piece.

The bolt has an abutment adapted to engage the abutment on the cocking piece towards the end of the backward movement of the bolt whereby on further backward movement of the bolt the cocking piece is moved therewith into a position in which it is engaged by the sear, subsequent forward movement of the bolt energizing the main spring.

A safety catch comprising a pivoted pawl-like member arranged for locking engagement with the bolt in the extreme forward position is provided to prevent accidental rotation of the bolt.

The cocking and trigger mechanism is mounted in a frame and constitutes a self-contained unit for fixing to the gun.

The rod to be projected is made in two parts screwed together so as to be adjustable for length.

The piercing end of the rod is guided between the side walls of a gutter, the space between the walls being adjustable by means of adjusting screws.

A part of the rod adjacent the piercing end is upwardly inclined and arranged to pass between upper and lower guides, one of which com-

prises an eccentric pin mounted for rotary adjustment, for the purpose hereafter described.

The said rod is guided in a bi-conical bearing supported in the stock of the gun, the rear end of the rod passing through the front end of the bolt and butting against a nose piece on the striker.

One way of carrying the invention into effect is illustrated in the accompanying drawings, 10 wherein—

Figure 1 is a longitudinal section of the butt end of the gun showing the mechanism in the uncocked position and Figure 1a is a section similar to Figure 1 showing the muzzle end of the gun.

Figures 2 and 2a are views similar to Figures 1 and 1a showing the parts in the cocked position.

Figure 3 is a cross-sectional view on line 20 III—III, Figure 2.

Figures 4 and 5 are cross-sectional views on lines IV—IV and V—V respectively, Figure 1a.

Figure 6 is a detail underneath plan view of the front end of the bolt and firing mechanism 25 frame.

Figure 7 is an end view of Figure 6.

Figure 8 is a cross sectional view on the line VIII—VIII of Figure 1a.

Figures 9, 10, 11 and 12 are perspective views 30 of the various parts constituting the cocking mechanism, and

Figure 13 is a perspective view showing the relationship of the gun to the target.

In the form illustrated in the drawings the 35 wooden stock comprises upper and lower parts 10, 11, screwed together and channelled interiorly so as, when assembled, to provide an interior space 12 to accommodate the operating mechanism, the butt 13 being integral with the lower part 11 of the stock. The dummy gun is similar to a real gun, for example a service rifle of any known type, as regards the construction of the front and back sights 14, 15, the parts to be handled by the user, and as regards its weight and the distribution of its weight, the latter being ensured by a ballast bar 16 screwed to the lower part 11 of the gun. In view of the closeness of the target, as will be clear hereafter, the position of the front sight is nearer the back sight than it would be in a corresponding service rifle, and the foresight blade is correspondingly thinner. The rod carrying the piercing end to be projected, comprises two parts 17, 17a, screwed together by means of a connector piece 1 welded to the part 17a, the part 17 receiving a lock nut

18. This arrangement permits the length of the rod 17, 17a to be accurately adjusted. The rod is mounted between metal side plates 19, 19a, closed at the fore end by an end plate 20 having a recess in its upper edge in which the rod 17 is slidably supported. The front end of the rod 17 is inclined upwardly and is slidably mounted between guides comprising a rotatably adjustable pin 20¹ having an eccentric groove 20² and a roller 21 mounted in a housing 21¹ said housing being pivotally mounted on pivot pins 21² adjustment about the pivot 21² being effected by a set screw 21³, and the rod 17 terminates in a pair of pins 22, 23. The eccentric groove in the bolt 20¹ provides an eccentric bearing pin for the rod. The piercing end of the rod when inside the stock, and when the gun is cocked (Figure 2a), is below the line of sight, but the arrangement described causes it during projection to move upwards into the line of sight (Figure 1a). If there is any small inaccuracy this can be corrected by rotary adjustment of the bolt 20¹ in its bearing to adjust correspondingly the position of the bearing pin, the position of the roller 21 being correspondingly adjusted by turning the set screw 21³ in the corresponding direction to raise or lower the housing 21¹ and the roller 21. Forward movement of the rod compresses springs 24, 25, arranged between sliding sleeves 26, 27, which then serve to return the rod after projection. The part 17 passes through a biconical passage bored through a pin 28 secured to a support 29 the sides of which pass between the sides of the ballast bar 16 and the sides of the stock and turn underneath the former, the bottom being screwed to the bottom of the stock. The pins 22, 23 are attached to the rod 17 by means of a socket 17¹ and the said socket slides between a gutter comprising a substantially U-shaped plate 2 (Figure 5) mounted in the muzzle of the gun, the width between the sides of the plate 2 being adjustable by adjusting screws 3, 4, the inner ends of which bear against the sides of the plate 2, which tend to spring apart.

The firing and trigger mechanism is mounted in a frame and constitutes a self-contained unit for fixing to the gun. Between the side walls of the unit U-shaped metal frame 30 is secured by screws a metal block 31 bored longitudinally to receive the hollow bolt 32, the front end of which is internally screwed to receive a screw-threaded shank 33 having a hexagonal flange. Between the bolt and this flange are threaded a guide plate 33¹ (Figure 6) to guide the bolt in its backward and forward movement, and a locking nut 33² to prevent movement of the threaded shank in use.

In Figure 7 the guide plate 33¹ is shown in full lines in the position in which the bolt lever 36 is shown in Figure 3. In this position a flat *a* on the flange *b* of the plate 33¹ butts against a stop *c* formed by cutting away part of the bottom of the frame 30. When the lever 36 is rotated to move the bolt backwards and forwards the guide plate 33¹ is rotated with the bolt into the position shown in dotted lines in which the two flats *a*, *a* on the flange *b* can slide along the top edges of the frame 30 thereby preventing rocking of the bolt relatively to the frame during the cocking movement.

The bolt 32 has a bayonet slot formed by cutting away part of its wall longitudinally as shown at 34 (Figure 10) for a substantial part of its length, the rear end of the slot being extended circumferentially on one side as shown 75

at 35. The bolt is operated by a bolt lever 36 (Figures 3 and 10) which is normally turned down to engage a recess 37 in the side wall of the frame 30 (Figures 3 and 9). The lever can be locked in this position by a safety catch comprising a pivoted pawl 38 pinned to a shaft 39 mounted in bearing blocks 9, and operable by a member 40 secured to said shaft. When the member 40 is operated to lock the bolt lever the pawl 38 swings upwards passing through an aperture in the bottom of the frame 39 and engages in a recess 41 in the rear edge of the bolt thereby preventing any rotation of the bolt.

The longitudinal slot 34 in the bolt is engaged by the upturned end of a cocking piece 42 which is slidably mounted in a passageway 43 formed between side plates 44, 45 (Figure 3) between which the trigger 46 and sear 47 are pivotally mounted, the bottom of the passageway on which the cocking piece 42 slides being constituted by a block 48 secured between the side plates 44, 45. The block 48 carries a pin 49 on which is disposed a coil spring 50 bearing at its free end on the sear 47 and tending normally to move the sear into, or hold it in, a position in which its upper edge engages a shoulder or stop 51 formed on the lower surface of the cocking piece 42.

The striker 52 is slidably mounted in a guide 53 comprising a disc bored centrally to admit the striker and fixed to, or integral with the hollow bolt, and extending across the internal diameter thereof. At the rear end of the striker 52 (Figure 12) is an enlargement 54 which can slide into and out of the rear end of the hollow bolt. A nose 55 is secured to the front end of the striker and has a rear flange or shoulder 56 which can be engaged by the upturned end of the cocking piece 42. The rear end of the rod 17 bears against the nose 55. The main spring 40 is made in two parts 57, 57¹ and surrounds the striker, the part 57 being disposed between the guide 53 and a movable sleeve 58, and the part 57¹ being disposed between the movable sleeve 58 and the nose 55.

45 The trigger is locked in an inoperative position until the gun is correctly shouldered by means of a spring-pressed rod 60 mounted in the butt of the rifle and having a recess 61 adjacent to the end thereof. When the gun is not correctly shouldered the unrecessed end of the rod prevents the operation of the trigger, but when correctly shouldered the recess 61 is moved over the trigger and allows the trigger to be pulled.

55 A hook 62 is secured to the bottom of the stock in order to mount the gun in operative association with a target carrying stand 69 (Figure 13), the hook engaging a yoke 69.

60 A metal strip 63 is screwed around the muzzle end of the stock to provide a needle guard. This guard includes a front plate 64 having an aperture through which is passed a screw 65 engaging in a nut 67 secured to the bottom of the gutter 2. The screw 65 serves for attaching a sight control frame to the muzzle of the gun for testing the accuracy of the position of pin 23 relatively to the line of sight.

65 In order to cock the gun the bolt lever is turned upwards through approximately 90° and the bolt 70 pulled to the rear. No resistance is encountered until the edge of the locking nut 33² engages against the upturned end of the cocking piece 42 whereupon further backward movement of the bolt moves the cocking piece slightly backward to enable the sear to re-engage the stop 51 on the

cocking piece. The bolt is now moved forwardly, compressing the spring 57, 57¹ against the nose 55 of the striker held fixed by the cocking piece 42 and sear 47 until the bolt lever can again be rotated back into the recess 37 whereupon the gun is cocked and ready to "fire." In order to "fire" the gun it must first be correctly shouldered to release the trigger, as above explained. When the trigger is pulled the sear releases the cocking piece, which in turn releases the striker to actuate the rod 17, 17^a, which is thus moved forwardly to project the pins 22, 23, to pierce the target. The springs 24, 25 are energized during the forward movement of the rod and serve subsequently to return the rod to the position shown in Figure 1a.

In a modification, instead of being in horizontal relationship the two pins 22, 23 may be in vertical relationship, the pin 23 being still arranged to come into the line of sight during projection.

We claim:

1. In a dummy gun for musketry and like training purposes in which a rod mounted in the stock of the gun and having means for piercing a target is adapted to be projected when the trigger is pulled, a cocking and trigger mechanism comprising: a hollow bolt; an abutment fixed to the bolt; a striker mounted within the bolt; an abutment carried on the striker; a main spring mounted on the striker between the said two abutments; a cocking piece arranged to engage the striker; a sear capable of engaging the cocking piece and to hold it and the striker immovable against the pressure of the main spring when the gun is cocked by backward and forward movement of the bolt; and a trigger for actuating the sear to release the cocking piece, whereby the energy of the cocked main spring is released to actuate the striker and the latter acts on the rod to project its piercing means from the gun.

2. A dummy gun having a cocking and trigger

mechanism as claimed in claim 1, in which the hollow bolt is formed with an L-shaped slot and the cocking piece has an abutment in engagement with the said slot, whereby the bolt is released to be slidden backwards and forwards, and rotated, relatively to the cocking piece.

3. A dummy gun having a cocking and trigger mechanism as claimed in claim 1, in which the hollow bolt is formed with an L-shaped slot and the cocking piece has an abutment in engagement with the said slot, whereby the bolt is released to be slidden backwards and forwards, and rotated, relatively to the cocking piece and in which the bolt also has an abutment adapted to engage the abutment on the cocking piece towards the end of the backward movement of the bolt, whereby on further backward movement of the bolt the cocking piece is moved therewith into a position in which it is engaged by the sear and the main spring is loaded by subsequent forward movement of the bolt.

4. A dummy gun having a cocking and trigger mechanism as claimed in claim 1 and further comprising a frame in which the cocking and trigger mechanism is mounted to form a self-contained unit for fixing into the gun.

5. A dummy gun having a cocking and trigger mechanism as claimed in claim 1 having a gutter the side walls of which serve as a guide for the piercing means of the rod and adjusting screws for adjusting the space between the said side walls.

6. A dummy gun having a cocking and trigger mechanism as claimed in claim 1 having upper and lower guides between which passes part of the rod adjacent the piercing means, which part is upwardly inclined, one of the said guides comprising an eccentric pin for rotary adjustment.
